(57) **CLAIM**

The ornamental design for a holding clamp, as shown and described.

DESCRIPTION

FIG. 1 shows a top view of the holding clamp in accordance with the invention.

FIG. 2 shows a side view of the holding clamp.

FIG. 3 shows a front view of the holding clamp.

FIG. 4 shows a perspective top view of the holding clamp.

FIG. 5 shows a perspective bottom view of the holding clamp.

FIG. 6 shows a rear view of the holding clamp.

FIG. 7 shows the holding clamp and two thin walls separately.

FIG. 8 shows a top view of the holding clamp and two thin walls in the assembled state; and,

FIG. 9 shows a rear view of the holding clamp and two thin walls in the assembled state.

The broken lines in the figures represent environment only and form no part of the claimed design.
